(57) **CLAIM**

The ornamental design for a combined water timer and manifold assembly, as shown and described.

DESCRIPTION

FIG. 1 is a perspective view of a combined water timer and manifold assembly;

FIG. 2 is a front elevation view of the combined water timer and manifold assembly;

FIG. 3 is a back elevation view of the combined water timer and manifold assembly;

FIG. 4 is a top plan view of the combined water timer and manifold assembly;

FIG. 5 is a bottom plan view of the combined water timer and manifold assembly;

FIG. 6 is a left side elevation view of the combined water timer and manifold assembly; and,

FIG. 7 is a right side elevation view of the combined water timer and manifold assembly.

The elements in broken lines show environmental structure and form no part of the claimed design.

1 Claim, 6 Drawing Sheets
